UNITED STATES PATENT OFFICE.

DILLARD M. NEWMAN, OF GALENA, OHIO, ASSIGNOR OF ONE-HALF TO ANCYL BEARDSLEE, OF COLUMBUS, OHIO.

MAIL-CATCHER.

1,115,330.

Specification of Letters Patent. Patented Oct. 27, 1914.

Application filed February 12, 1914. Serial No. 818,180.

To all whom it may concern:

Be it known that I, DILLARD M. NEWMAN, a citizen of the United States, residing at Galena, in the county of Delaware and State 5 of Ohio, have invented certain new and useful Improvements in Mail - Catchers, of which the following is a specification.

My invention relates to mail catchers and aims particularly to provide a device of 10 this type for catching the mail from a moving train.

I have found that it frequently happens that mail bags are caused to roll under the train and be cut up when they are simply 15 tossed out of the mail car and again they are apt to roll down the side of a hill if they should happen to be thrown from a mail car while passing along a hill. Further, where the mail is simply tossed out of the car, the 20 official is depended upon to throw it out at the correct place.

My invention takes the form of a means for suspending a mail sack or a plurality of sacks from the side of a moving train and 25 causing the suspended sack to strike an abutment to be thereby removed.

My invention also contemplates the provision of a bracket arm movable to a position inside or outside of the car, as may 30 be desired. This bracket arm is caused to be held in its outside operative position in a manner that when the sack strikes an abutment, the bracket arm will be permitted a rearward movement to alleviate the impact as much as possible.

The preferred embodiment of my invention is shown in the accompanying drawings, in which similar characters of reference designate corresponding parts, and in 40 which:

Figure 1 is a view showing my invention applied to a mail car, the car itself being shown in section and somewhat diagrammatically, Fig. 2 is an enlarged front elevation of my invention itself, showing the car as broken away and showing the bracket arm in broken lines in two different positions, Fig. 3 is a top view of a member forming the lower bearing for the vertical rod 45 used by me, Fig. 4 is a section of a structure shown in Fig. 3, Fig. 5 is a section of the upper bracket for the vertical rod, Fig. 50 6 is a bottom view of the bracket shown in

Fig. 5, Fig. 7 is a central vertical section of the bracket arm itself, Fig. 8 is a bottom view of this bracket arm, Fig. 9 is a face view of a blanket member used by me, Fig. 10 is a view showing this blanket member folded to form a sack, and, Fig. 11 is a detail view of the end portion of the mail sack 60 supporting bracket.

In the drawings, I have designated the mail car as 1, which mail car is provided with an opening 2 and wheels and axles 3, running upon track-rails 4. My invention 65 is itself applied directly adjacent the door opening 2 and comprises a vertical rod 5, suitably journaled at its upper end by means of the bearing 6 and at its base by means of the bearing 7, which is shaped after the 70 manner of a thrust bearing, being provided with a socket such as shown at 8. The rod 5 is further rigidly provided with a key 9, which key is located somewhat above the level of the floor as is more clearly shown 75 in Fig. 2. Upon this rod 5 is adapted to slide a bracket member 10, this bracket member being also rotatably mounted upon the rod and being further provided with a key-way 11 adapted to coöperate, under 80 certain conditions, with the key 9. The body 12 of the bracket 10 is provided at its lower end with downwardly projecting V-shaped lugs 13, which lugs form a cam face for the bracket itself and are adapted to coöperate 85 with similarly formed depressions 14 in the upper portion of the lower bearing 7.

I have shown a supporting standard 15 having a bracket arm 16, upon which is adapted to be hung a mail bag or two to be 90 collected by the train in passing. This is all of the well known type and further description of this feature, is not believed to be necessary. However, I have also provided an abutment to serve in connection with the 95 bracket 10, this abutment being shown as a post 17 securely held in position and being further provided with brace rods 18 which brace rods are disposed in planes oblique to a plane passing centrally through the 100 post 17 and parallel with the track rails. The purpose of this oblique arrangement will be clearly set forth hereinafter.

It is often desirable to unload a plurality of sacks at one point and in order that my 105 invention may apply to cases of this kind,

I have provided a blanket 19, which blanket is adapted to be folded up as is shown in Fig. 10, to form a sack to contain the desired number of bags. It will be noted that 5 the four corners of this blanket are provided with rings, the rings 20 being somewhat larger in diameter than the ring 21. Should it be desired to form a sack out of this blanket, the mail bags are placed thereon and the four corners raised and the small ring 21 being thereafter passed through each of the larger rings 20. After this has been done, the entire mass may be held supported on the bracket arm by means of the small 15 ring 21.

The operation of my device is as follows: As the train approaches a station, the official places the mail sack upon the bracket 10. It is to be understood that the bracket 10 may 20 be slid vertically upon the rod 5 and, when the key-way 11 is caused to register with the key 9, the entire bracket may be moved to some considerable distance above the floor level of the car and swung inwardly to the 25 position shown in broken lines in Fig. 1. It is in this position that the official may most conveniently place the mail sacks on the bracket for delivery. After this, the bracket may be swung outwardly and allowed to descend to the position shown in full lines in 30 Fig. 1, in which position the cam faces upon its lower side caused by the V-shaped projections 13, are caused to coincide with the V-shaped depressions 14 formed in the end 35 thrust bearing 7. Because of these V-shaped formations, the bracket will be maintained in its outermost position against any ordinary wind resistance, but upon the mail bag striking the post 17, the shock will be somewhat absorbed by the cam 13 riding upon 40 the upper face of the end bearing 7 and be swung rearwardly to assume a position at ninety degrees to that shown in Fig. 1. Further, the braces 18 being disposed in the 45 peculiar oblique manner as has been heretofore related, form a pocket for securely confining the discharged bags and thus prevent them from falling beneath the wheels of the train or becoming otherwise lost. It will be 50 noted that I have extended the keyway 9 downwardly to a position slightly clearing the bracket 10 when the V-shaped projections 13 are out of their corresponding sockets 14. This structure prevents the bracket 55 itself from being forced up the vertical rod

5 when the sack is being removed, as might be the case when the train traveled at a high rate of speed.

In order to maintain the sack upon the bracket 10 with comparative security, I 60 have notched the end as is shown at 22 and provided this end with a spring clip of the nature shown at 23. This spring clip is given its resiliency by means of the abrupt bend as shown and is locked in position by 65 engaging the extreme forward end of the arm. The notch 22 and the bend of the clip provide a space sufficient to accommodate the ring 21 when the same is suspended on the free end of this arm and the clip may 70 then be moved into the position shown in full lines in Fig. 11, to resiliently maintain the sack in such position. It will be understood that the mail sack striking an abutment, the force will be sufficient to disengage 75 the spring clip to move it to the position shown in broken lines.

What I claim, is:

1. A mail catcher for railroads comprising a vertical rod carried by a car at its door 80 opening, a key on said rod at some distance above the floor level of the car, a bracket slideable and rotatable on said rod and having a key-way therein to fit said key, a cam face on the lower end of said bracket, and 85 a bearing for the lower end of said vertical rod and formed to form a seat to coincide with said cam face when said bracket is swung to its outermost position.

2. A mail catcher for railroads comprising 90 a vertical rod carried by a car at its door opening, brackets slideable and rotatable on said rod and having a key-way therein, a cam face on the lower end of said bracket, a bearing for the lower end of said vertical 95 rod and formed to form a seat to coincide with said cam face when said bracket is swung to its lowermost and outermost position, and a key on said vertical rod terminating at a point to clear the upper face of said 100 bracket when it is in its lowermost position and having its cam face disposed at ninety degrees to the complementary seat formed in said bearing.

In testimony whereof I affix my signature 105 in presence of two witnesses.

DILLARD M. NEWMAN.
